UNITED STATES PATENT OFFICE.

CHARLES R. STEDMAN, OF CLEVELAND, OHIO.

VESSEL-GUIDING MECHANISM.

1,165,032.

Specification of Letters Patent. Patented Dec. 21, 1915.

Application filed January 21, 1914. Serial No. 813,357.

To all whom it may concern:

Be it known that I, CHARLES R. STEDMAN, a citizen of the United States, residing at Cleveland, in the county of Cuyahoga and State of Ohio, have invented a new and useful Improvement in Vessel-Guiding Mechanism, of which the following is a specification, the principle of the invention being herein explained and the best mode in which 10 I have contemplated applying that principle so as to distinguish it from other inventions.

My invention has general reference as the title indicates, to vessel guiding mechanism 15 while more particularly to a contrivance for effecting an auxiliary propulsion in a direction other than in line with the keel.

The object of the invention is to provide the vessel itself with a positive control for 20 turning it in either direction or for moving it in a sidewise direction thereby avoiding expensive tugging assistance and affording absolute precision in approaching a dock.

Incidental objects have been first, to accomplish the results sought in a comparatively simple and economical manner; second, to require little space within the hull; and third to avoid under ordinary circumstances all exteriorly projecting parts.

30 My inventive conception is embodied in means which are hereinafter explained and variously combined in the claims, while the annexed drawing and particular description thereof together set forth in detail certain 35 means constituting my invention, the disclosed means, however, being but one of various mechanical forms in which the principle of my invention may be applied.

Figure 1 is an elevation of the hull of a 40 vessel partly in section showing the relative location and corresponding appearance of a double embodiment of my invention and one detail in dotted lines in an altered position. Fig. 2 is an enlarged end view partly in 45 section showing certain features of my invention proper. Fig. 3 is a side view of the same with portions broken away and other portions in section. Fig. 4 is a similarly enlarged section showing certain inclosing 50 members. Fig. 5 is a section on line 5—5 of Fig. 4 looking in the direction of the arrows. Fig. 6 illustrates in detail certain operating mechanism. Fig. 7 is an enlarged plan of the driving mechanism in 55 one end of the vessel.

In Fig. 1 the entire hull of a vessel has been designated by the reference character A. Mounted in this hull is shown an engine, a stern post carrying the rudder and a propeller inclosed by the stern post. In 60 the exemplification seen in the drawing the hull is provided near each end and only a short distance above the keel with openings α' extending therethrough from side to side and in this instance transversely of the keel. 65 The sides of the vessel are provided exteriorly with annular recesses α^2 surrounding the openings α' .

Extending between the two forward and likewise between the two rearward of the 70 openings respectively I seat a pair of cylindrical tubes B. These tubes B while open at each end are water-tight with respect to the hull of the vessel.

Secured to the interior of the tubes B in 75 any approved manner are four supporting hangers b' . These hangers are equispaced and otherwise arranged such that alternate ones are mainly parallel and adjacent ones transverse with respect to each other, as 80 clearly seen in Fig. 2. The hangers b' are adapted to support between their innermost extremities b^2 a shaft housing b^3 provided at opposite ends with bearing members b^4 . This construction is represented in Figs. 85 2 and 3. An auxiliary propeller shaft b^5 is mounted in the bearings b^4 and concentrically of the tube B. Within the housing b^3 the shaft b^5 has fixedly keyed upon it a bevel gear b^6 . An exteriorly projecting 90 portion of the shaft b^5 has fixed to it any conventional type of propeller b^7 . This propeller is in practice preferably of a reversible type, and since nothing is claimed in 95 regard to this feature its detailed construction is omitted.

The bottom of the tube B is provided with draining facilities as suggested by the pipe b^8 seen in Fig. 1. Opposite ends of the tube B are provided with a plurality of parallel upright vanes b^9 whose smallest dimension is seen to be transverse with respect to the imaginary axis of the tube B. These vanes b^9 are illustrated in Figs. 4 and 5. Their purpose is to prevent entrance into 100 the tubes of large objects likely to interfere with or obstruct the propeller b^7 . An auxiliary driving shaft C may be operatively connected at will with the engine through 105 the medium of a clutch c' . This clutch is 110

shown in Fig. 1 and since its particular construction is of no moment here, a detailed representation of it has also been omitted. The other extremity of the shaft C projects into the forward tube B and also into the housing b^3 where it is provided with a complementary bevel gear c^2 which is in mesh with the bevel gear b^6 . In this manner as will now be perceived, power may be transmitted from the engine such that the rotation of the shaft C effects the rotation of the shaft b^5 and hence the revolution of the propeller b^7 .

Supported upon each end of the tube B is a casing D. This casing is secured to the side of the hull by means of a plate d' , provided interiorly of the casing D with an opening d^2 . Seated in the opening d^2 and projecting into the casing D is a bearing member d^3 . About midway of the casing D is an upright partition d^4 provided with a smaller opening d^5 which is in line with the imaginary axis of the bearing d^3 .

A stub shaft E is mounted for movement in the bearing d^3 . This shaft is provided inwardly adjacent its journal in the bearing d^3 with a spline e' and in turn inwardly adjacent the spline e' the shaft E is grooved circumferentially as designated by e^2 and best seen in Fig. 6. The remainder e^3 of the shaft E is of smaller diameter and extends through the opening d^5 in the partition d^4 . Upon the extremity of this reduced portion of the shaft E a pin e^4 is provided, while interposed between this pin and the partition d^4 is a compression spring e^5 . Keyed upon the spline e' is a worm gear e^6 . An upright operating rod e^7 extends into the casing D, and on its inner extremity supports a pinion e^8 adapted to mesh with the grooves e^2 . A second operating rod e^9 likewise extends through the casing D and on its extremity supports a worm e^{10} adapted to mesh with the worm e^6 . Mounted eccentrically upon the extremity of the shaft E is a circular door F adapted to occupy as a close mechanical fit the annular recess a' and effect therewith in conjunction with suitable packing a water-tight closure. That one of the tubes B which extends across the stern of the vessel has the main shaft C extending into it at which point the latter carries a sliding clutch c^3 whereby to connect or disconnect a beveled gear c^4 . Mounted interiorly of the stern tube B are bearings a^3 adapted to support axially of said tube a stub-shaft a^4 upon which is mounted a propeller c^5 and also another beveled gear a^6 adapted to mesh with the bevel gear c^4 . In this manner depending upon whether the gear c^4 is in or out of engagement with the gear a^6 the lateral propulsion of the stern of the vessel may be additionally effected or not as the case may be.

The operation of the mechanism for mov-

ing a door F, assuming the same to be in its closed position as seen in Fig. 4, is therefore as follows: Prior to establishing a connection between the shaft C and the engine preparatory to driving the propeller b^7 , the two doors F of any particular tube B should be opened and preferably entirely removed from in front of the opening thereto. The rod e^7 is first rotated either by hand or otherwise, whereupon the shaft E is moved outwardly against the action of the spring e^5 . During such outward movement the door F is necessarily moved out of the recess a' and beyond the outer surface of that portion of the hull A which is immediately above the casing D. Next, the rod e^9 is rotated and hence also the worm e^6 . In consequence of the rotation of the latter the shaft E is itself rotated and the door F swung upwardly as indicated in dotted lines in Fig. 1. After the two doors F of one or the other of the tubes B have been opened, power may be transmitted to the propeller b^7 whereby the water is propelled through the tube B and the corresponding end of the vessel caused to move in the reverse direction. It is obvious that a simultaneous operation in reverse directions of the propellers in the two tubes B will contrive to turn the vessel even more quickly, and similarly their simultaneous operation in the same direction will cause the vessel as a whole to move sidewise.

My invention being thus described with sufficient thoroughness, what I desire to secure by Letters Patent and therefore claim specifically, is:

1. A vessel guiding mechanism comprising the combination of a hull having a compartment opening therethrough and closed with respect thereto, propulsion means disposed within said compartment, power means, doors supported at said openings and movable toward and away from the planes thereof respectively, and means for actuating said doors.

2. A vessel guiding mechanism comprising the combination of a hull having a compartment opening therethrough and closed with respect thereto, propulsion means disposed within said compartment, power means, said hull being recessed adjacent said openings, doors seated in said recesses respectively and flush with the exterior surface of said hull, and movable means supporting said doors and adapted to successively outwardly move and swing the same from said recesses.

3. A vessel guiding mechanism comprising the combination of a hull formed with a compartment closed with respect thereto and affording open communication with the supporting body of water on opposite sides thereof, a shaft mounted in said compartment, and extending in the direction of the

openings of the latter, a propeller upon said shaft, power means operatively connected with said shaft, a stub shaft substantially parallel to the first mentioned shaft and adapted for rotary and endwise movement, a door upon the outer extremity of said stub shaft and fitted to one of said openings, means for moving said shaft in the direc-

tion of its own axis and distinct means for rotating said shaft. ¹⁰

Signed by me, this 19th day of January, 1914.

CHARLES R. STEDMAN.
